UNITED STATES PATENT OFFICE.

JOHN H. CHAMBERLIN, OF ELLISDALE, NEW JERSEY.

DESIGN FOR A CAR-STEP.

SPECIFICATION forming part of Design No. 35,177, dated October 8, 1901.

Application filed July 22, 1901. Serial No. 69,340. Term of patent 14 years.

To all whom it may concern:

Be it known that I, JOHN H. CHAMBERLIN, a citizen of the United States, residing at Ellisdale, in the county of Monmouth and State of New Jersey, have invented and produced a new and original Design for Car-Steps, of which the following is a specification, reference being had to the accompanying drawings, forming a part thereof.

10 Figure 1 is a front view, Fig. 2 is a side view, and Fig. 3 is a top view, of my new design.

In all three views like parts are designated by the same figures of reference.

15 As shown in the drawings, the leading or material feature of my design consists of a back 1, narrower at the bottom than top, connected to the rectangular sides 2 2, having the edge bars 3 3, with the offsets 4 4 at their

upper extremities. A bottom edge bar 5 connects the lower extremities of the side bars 3 3. A rectangular bottom 6 is supported by the lower edge of the back 1 and the front bar 5. Rectangular open spaces 7 7 are provided between the edges of the bottom 6 and 25 the sides 2 2.

Having now described my invention, what I claim as new, and desire to secure by Letters Patent, is—

The design for a car-step, as herein shown 30 and described.

In testimony whereof I have signed my name to this specification in the presence of two subscribing witnesses.

JOHN H. CHAMBERLIN.
